(57) **CLAIM**

(21) Appl. No.: **29/149,924**

The ornamental design for a preform mold stripper plate, as shown and described.

(22) Filed: **Oct. 23, 2001**

DESCRIPTION

(51) LOC (7) Cl. **15-09**

FIG. 1 is a front view of the preform mold stripper plate;

(52) U.S. Cl. **D15/135**

FIG. 2 is a bottom view thereof;

(58) Field of Search D15/135-137;

FIG. 3 is a side view thereof;

425/DIG. 240, DIG. 119, DIG. 118, DIG. 117,

FIG. 4 is a top view thereof;

DIG. 38

FIG. 5 is a side view thereof;

FIG. 6 is a back view thereof;

FIG. 7 is a front isometric view thereof; and,

FIG. 8 is a back isometric view thereof.
